UNITED STATES PATENT OFFICE.

MAURICE A. SMITH, OF JEANNETTE, PENNSYLVANIA, ASSIGNOR TO MCKEE GLASS COMPANY, OF JEANNETTE, PENNSYLVANIA, A CORPORATION OF PENNSYLVANIA.

DESIGN FOR A GLASS BOWL.

50,960.

Specification for Design. Patented June 19, 1917.

Application filed March 16, 1917. Serial No. 155,362. Term of patent 3½ years.

To all whom it may concern:

Be it known that I, MAURICE A. SMITH, a citizen of the United States, and residing at Jeannette, in the county of Westmoreland, State of Pennsylvania, have invented a new, original, and ornamental Design for a Glass Bowl, of which the following is a specification, reference being had to the accompanying drawing, forming part thereof, in which—

Figure 1 is a top plan view, and Fig. 2 is a side view of a glass bowl showing my new design.

I claim:

The ornamental design for a glass bowl, as shown.

MAURICE A. SMITH.

Witnesses:

D. M. SMITH,

D. B. PILKEY.
